D. KOPS.
APPAREL CORSET.
APPLICATION FILED MAR. 13, 1919.

Patented June 17, 1919.

UNITED STATES PATENT OFFICE.

DANIEL KOPS, OF NEW YORK, N. Y.

APPAREL-CORSET.

1,307,132.

Specification of Letters Patent. Patented June 17, 1919.

Application filed March 13, 1919. Serial No. 282,335.

To all whom it may concern:

Be it known that I, DANIEL KOPS, a citizen of the United States, residing in the borough of Manhattan, city, county, and State of New York, have invented an Improvement in Apparel-Corsets, of which the following is a specification.

This invention relates to an apparel corset and more particularly to that type of apparel corset in each complementary half of the body of which there is employed a self-reducing strap, and also a depending skirt member which is continuous from the rear to the front medial lines of the garment. I am aware that heretofore various forms of apparel corsets have been constructed in which self-reducing straps have been employed. I am also aware that heretofore various forms of apparel corsets have been constructed in which there have been depending skirt members extending from the rear to the front medial lines of the garment. So far as has come to my knowledge however, no corset garment has ever been heretofore constructed in which a self-reducing strap has been employed in conjunction with a depending skirt member continuing to the front medial lines of the garment. In all instances I believe in which heretofore self-reducing straps have been employed in corset garments, there have been either no depending skirt members or the skirt members have been divided in the lower front sections of the garment or have terminated forward of the hip sections of the garment so that the functions of the self-reducing straps and the functions of the depending skirt member at the front of the garment would not interfere or conflict with one another. The obvious tendency of employing a self-reducing strap with a continuous depending skirt member has heretofore been to cause the skirt member forward of the hip sections to pucker and wrinkle.

I have found it possible to overcome this objection and thus combine the use of a self-reducing strap in a corset in which

there is also employed a depending skirt member which is continuous from the back to the front medial lines of the garment, and the corset made in accordance with my present invention will be hereinafter more particularly described.

In the drawing:

Figure 1 is a perspective view of the corset garment made in accordance with my present invention.

Fig. 2 is an enlarged front elevation of my improved corset.

Fig. 3 is an enlarged cross-section on line 3—3 Fig. 2, and Fig. 4 is a front elevation illustrating a modified form of self-reducing strap.

Referring to the drawing, this invention preferably relates to an apparel corset which is made in the customary complementary halves indicated respectively at 10 and 11. In these corset body halves there are provided the usual front steels 12 and 13, fitted with suitable clasps 14 by which the steel sections of the garment may be connected at the front thereof, and in each corset body half there is provided along the rear edge thereof a series of eyelets which are indicated at 15 and 16 in the respective corset body halves and through which there is threaded the usual lace 17 by which the parts of the garment are adjusted to position for use on the body of the wearer. Furthermore, in each corset body half, as made in accordance with my present invention, there are depending skirt members indicated at 18 and 19, which continue or extend unbrokenly from the back to the front medial lines of the garment. In each corset body half also, there is a self-reducing strap, these being indicated in the respective corset body halves at 20 and 21. Each of these self-reducing straps is similar and therefore but one of them will be hereinafter specifically described.

The self reducing strap 20 is connected at one end to the body of the corset body half 10 along the line of stitching 22 which is appreciably forward the hip section of the

garment. At its forward end this self-reducing strap is provided with eyelets 23 either one of which is adapted to engage with a hook 24 provided for this purpose on 5 the lower front portion of the corresponding front steel so as to make the self-reducing strap adjustable to position. In addition to being secured to the corset body half along the line of stitching 22, this self reducing strap 20 is also secured thereto along 10 the lines of stitching 25, 26 and 27 by which the bone or stay pockets 28 and 29 are also formed. This, as will be understood, provides a space or pocket indicated at 30 between that portion of the self-reducing straps lying between the line of stitching 22 and the line of stitching 27 so that the 15 relative positions of these parts of the garment are maintained irrespective of the position to which the self-reducing strap may be adjusted, and this as will be furthermore understood, prevents the rumpling or puckering of the depending skirt forward of the hip section.

20 Also as indicated in Fig. 2, the self-reducing strap 20 may be provided with a reinforcing strip 31 extending longitudinally thereof in the line of pull or strain to which the same is subjected, and this is suitably 25 secured to the self-reducing strap adjacent the edges of the reinforcing strip by lines of stitching indicated at 32.

As shown in Fig. 4, instead of running the reinforcing strip 31 in a substantially central position in the self-reducing strap, as 30 shown in Figs. 1 and 2, this reinforcing strip, as indicated at 35 in Fig. 4, may extend along the self-reducing strap substantially 35 parallel to the lower edge thereof. As will be understood when the strip is run centrally of the self-reducing strap, it merely acts in assistance to the self-reducing strap in performing the self-reducing function, whereas when extended in a position substantially 40 parallel to the lower edge of the self-reducing strap, this reinforcing strip acts as an uplifting member, tending to support the abdomen of the wearer of the garment.

45 Also as is customary, the depending skirt sections may be provided with hose supporters straps indicated at 33 and 34.

I claim as my invention:

1. In an apparel corset and in each corset body half thereof, a depending skirt member extending continuously from the back to the front medial lines of the garment, and a self-reducing strap attached at one end to the corset body half adjacent the hip section 55 thereof and also to the corset body half forward of the hip section thereof whereby the self-reducing strap may be adjusted to a position without interfering with the even

continuity of the lower front portion of the depending skirt member.

65

2. In an apparel corset and in each corset body half thereof, a depending skirt member extending continuously from the back to the front medial lines of the garment, a self-reducing strap attached at one end adjacent the hip section of the corset body half and also to the corset body half an appreciable distance forward of the hip section whereby the self-reducing strap does not interfere with the function of the continuous depending skirt member, and means for adjustably connecting the self-reducing strap at its opposite end to the lower front section of the corset body half.

70

3. In an apparel corset and in each corset body half thereof, a depending skirt member extending continuously from the back to the front medial lines of the garment, and a self-reducing strap secured at one end to the corset body half by a line of stitching running transversely thereof and longitudinally of the corset body half, the said self-reducing strap being also secured intermediate of its ends to the corset body half by additional lines of stitching running transversely thereof and longitudinally of the corset body half.

80

4. In an apparel corset and in each corset body half thereof, a depending skirt member extending continuously from the back to the front medial lines of the garment, and a self-reducing strap secured at one end to the corset body half by a line of stitching running transversely thereof and longitudinally of the corset body half, the said self-reducing strap being also secured intermediate of its ends to the corset body half by additional lines of stitching running transversely thereof and longitudinally of the corset body half, and means whereby the opposite end of the self-reducing strap may be adjustably connected to the corset body half at the lower front portion thereof.

90

5. In an apparel corset and in each corset body half thereof, a depending skirt member extending continuously from the back to the front medial lines of the garment, and a self-reducing strap secured at one end in the corset body half forward of the hip section by a line of stitching running transversely of the self-reducing strap and longitudinally of the corset body half, of the corset body half and also secured to

95

the corset body half by lines of stitching running transversely of the self-reducing strap and longitudinally of the corset body half, which latter lines of stitching also define portions of stay pockets formed in the corset body half.

100

6. In an apparel corset and in each corset body half thereof, a depending skirt member extending continuously from the back to the front medial lines of the garment, and a self-

115

120

125

reducing strap attached at one end to the corset body half adjacent the hip section thereof and also to the corset body half forward of the hip section thereof whereby the 5 self-reducing strap may be adjusted to position without interfering with the even continuity of the lower front portion of the de-

pending skirt member, the said self-reducing strap having a reinforcing strip secured thereto and extending longitudinally 10 thereof.

Signed by me this 7th day of March, 1919.

DANIEL KOPS.
